UNITED STATES PATENT OFFICE.

CURT KUENTZEL, OF AKRON, OHIO, ASSIGNOR TO THE R. F. GOODRICH COMPANY, OF NEW YORK, N. Y., A CORPORATION OF NEW YORK.

TIRE-BUILDING APPARATUS.

Application filed February 7, 1921. Serial No. 442,952.

To all whom it may concern:

Be it known that I, CURT KUENTZEL, a citizen of the United States, residing at Akron, in the county of Summit and State 5 of Ohio, have invented a certain new and useful Tire-Building Apparatus, of which the following is a specification.

This invention relates to tire-building apparatus and particularly to "stitching" devices and movements for the same.

The object of my invention is to provide improved automatic means for controlling the movement of stitching tools and particularly to provide quick-acting means adapted 15 to apply a predetermined pressure to each part of the work and to withdraw the tools out of the way at the end of each operation. The particular embodiment described herein and illustrated in the accompanying drawings 20 is adapted to perform this stitching operation upon the tread in an improved manner.

Of the accompanying drawings:

Fig. 1 is a side elevation of a part of a 25 tire-building machine embodying a preferred form of my invention, showing the tread stitching-roller tools out of operative position.

Fig. 2 is a similar view showing the tread 30 stitching tools in operative position.

Fig. 3 is a detailed section on the line 3—3 of Fig. 2.

Fig. 4 is a section in the middle plane of 35 the work through the tool-head, showing the position of the parts when the stitching tools are out of contact with the tire.

Referring to the drawings, 10 is a base, 40 supporting a frame 11, upon which is revolvably mounted an annular core 12. 13 is a tire carcass upon said core and 13^a is a 45 tread on said carcass. 14 is a lever formed with a bracket 14^a, said lever being pivoted at one end for vertical movement upon a revolvable shaft 15 which extends from the 50 frame 11. Upon the outer end of the lever 14 is a tool-carrying head 16 which will be further described hereinafter. Mounted upon the base 10 in alignment with the lever 14 are actuating means therefor comprising 55 a bracket 17, a toggle 18 connecting said bracket with the arm 14, a power cylinder 19 of which the piston-rod 20 is shown, fluid connections 19^a therefor, and a piston-rod 60 guide 21. The outer end of the piston-rod 56 is provided with a fork 22. 23 is a gimbal

ring pivoted between the forks of said piston rod at their outer ends. 24 is a rod having one end pivotally connected to the elbow of the toggle 18 and the other end 60 slidably extending through the gimbal ring 23 and between the prongs of the fork 22. 25 is a coil spring encircling the rod 24 between the gimbal ring 23 and an adjustable nut 26 upon the end of said rod, said spring 65 being adapted to impel said rod toward the cylinder 19. 27 is an adjustable stop-bolt threaded into the base 10 and adapted to receive a lug 28 formed upon the lower arm of the toggle 18 to limit the retractive movement of the toggle.

29, 29 are tread-stitching tools in the form 70 of rollers mounted upon the outer end of the lever 14 in a manner presently to be described. 30 is a U-shaped stop-roller journaled upon the end of an adjustable bolt 31 75 secured upon the arm 14, the stop-roller 30 being in alignment with the middle plane of the tire and adapted to contact with the tread thereof when the stitching tools have reached a predetermined position relative to 80 the tire.

Referring to Figs. 3 and 4 showing the tool-head in detail, 32 is a horizontal box-shaped housing disposed crosswise of the lever 14 at its outer end and formed with a lengthwise elongated opening through its top wall and with two spring-enclosing sleeves extending downward from its bottom. 33, 33 are end plates for said housing 32, formed with bearings 34 in the centers 85 thereof for a right-and-left threaded screw-shaft 35. Said shaft is formed with a stop-block 34^a between the reversed threads. 36 is an open-ended box-shaped member within the housing 32 and interfitting therewith 90 laterally and longitudinally, but vertically 95 slidably therein and formed with an elongated opening through its top wall registering with that of the housing 32. Compression springs 37, 37 are interposed within 100 the aforementioned sleeves between the floor of the inner box 36 and plugs which are threaded into the lower ends of the sleeves. 38, 38 are tool-carrying brackets upon the upper ends of which the tread-stitching 105 tools 29, 29 are rotatably mounted on axes approximately parallel to that of the tire core. The brackets 38 extend downward through the elongated openings or slots in 110 the top walls of the housing 32 and the in-

ner box 36 and are slidable lengthwise thereof. Their lower ends slidably fit the interior of the inner box 36 and are formed with oval, horizontal holes 39, 39, which are 5 threaded at their upper ends only, with segmental female right-hand and left-hand threads respectively, corresponding to the reversed male threads of the shaft 35, which extends through said holes 39, 39. 40 is a 10 tension spring interposed between the brackets 38. 41 is a sprocket wheel secured to the protruding end of the right-and-left threaded shaft 35 and connected with a power sprocket 42 on the shaft 15 by a drive 15 chain 43.

In the operation of the device the tire core 12 carrying the carcass 13 with the tread 13^a attached thereto along its middle line being mounted upon the machine, fluid under pressure is admitted to the cylinder 19 driving the piston to the right as viewed in Fig. 1, partially straightening the toggle 18 and compressing the spring 25, thereby 20 swinging the arm 14 vertically into operative position with the tread stitching tools 29 bearing against the tread at its middle line. Up to this time the tools are held together, their brackets abutting against the stop-block 34^a, by the spring 40, the threads 25 of the screw shaft 35 being out of mesh with the threads at the top of the holes 39 in the brackets 38 by reason of the elevated position 30 of the inner box 36 and the brackets 38 due to the action of the springs 37, as shown 35 in Fig. 4.

As the straightening toggle 18, actuated by the spring 25, continues to elevate the arm 14 and housing 32 and the threaded shaft 35 after the tools 29 have come in contact with the thread and are thereby checked in their upward movement, their pressure against the tread overcomes the springs 37, permitting the housing 32 carrying the threaded shaft 35 to continue its upward 40 movement and bring the threads of said shaft into mesh with the segmental threads at the top of the holes 39 in the brackets 38.

Rotation of the core, and of the threaded shaft 35 by the sprockets 41 and 42 and the 45 chain 43, meanwhile may have been started, or they may be set to revolving after the toggle device has brought the tools 29 into contact with the thread. As soon as the right-and-left threads of the shaft 35 mesh 50 with those of the brackets 38 their rotation forces gradually apart the brackets 38. While said brackets and the thread stitching tools 29 carried thereby are thus driven apart by the action of the reversed threads, 55 against the action of the spring 40, the tools are rotated by their frictional contact with the revolving tire. As the tools move laterally of the tire, stitching the tread thereon, the toggle device constantly presses them 60 upward against the tire tread, causing their 65

working edges with suitable pressure to follow the lateral contour of the tire and carry the stitching operation progressively from the middle to the edges of the tread. When they have reached the desired position laterally and radially of the tire, as predetermined by the setting of the bolt 31 carrying the stop roller 30, the latter, coming in contact with the tire, stops the upward movement of the lever 14 and the tread stitching 70 operation is completed. The fluid pressure in the cylinder 17 is then released or reversed, returning the arm 14 to the inoperative position shown in Fig. 1. As the tool head recedes from the tire, releasing the 75 pressure upon the springs 37, the latter raise the box 36 within the housing 32 to the position shown in Fig. 4, thus throwing the segmental threads in the bracket 38 out of mesh with the threaded shaft 35 and permitting the spring 40 to draw the brackets back together against the stop-block 34^a, ready to 80 repeat the operation.

An advantage of the spring connection 25 between the cylinder 19 and the toggle 18 is 85 that the parts may be so proportioned that the spring 25 will continue to expand after the piston has traversed its full stroke and a diminishing force will thus be exerted upon the toggle 18, compensating the increased mechanical advantage of the toggle in its more straightened position and of the wedging action of the tools as they pass onto the sides of the tire, thus preventing too great a pressure of the tools in the side regions of the tire. By varying the tension of spring 25 and by substituting toggles of different mechanical advantages various gradations in the pressure of the stitching tools as they move around the tire may be 95 obtained, and the same gradation of pressure may be applied to successive tires.

Various modifications obviously may be used without departing from my invention, and I do not desire to limit my rights to the 100 specific construction shown in this embodiment.

I claim:

1. In a tire-building machine, the combination of a revoluble tire core, a stitching roller mounted for rotation and for movement inwardly around the tread and side surfaces of a tire on said core, means for feeding said roller away from the middle plane of the core, a power member for feeding it in the general direction of the core axis, and a yielding connection between said power member and roller.

2. In tire building apparatus the combination of a tire core, means for supporting and circumferentially rotating said core, a stitching roller adapted to operate upon a tire mounted on said core, yielding means for urging said stitching roller generally toward the axis of rotation of said 125 130

- core, a drive member, and positive feeding means adapted to be driven thereby for feeding said roller laterally of the core, said feeding means being adapted automatically to be placed in driving relation with said drive member as said stitching roller contacts the work, by the force of such contact.
3. In tire building apparatus the combination of a tire core, means for supporting and circumferentially rotating the same, a stitching roller adapted to operate upon a tire mounted on said core, a support for said stitching roller adapted to be presented to and retracted from the tread portion of said tire, driving means carried by said support and adapted to be thrown into effective operation by pressure of said roller against the work, to feed said roller laterally of the core, and yielding means for automatically throwing said driving means out of effective operation when said support is retracted from the work.
4. In a tire-building apparatus the combination of an annular tire core, means for rotating the same, a revolvable stitching member, mechanism adapted to feed said stitching member toward the axis of the core, a screw, and a member formed with segmental threads normally disposed in inoperative relation to said screw but adapted automatically to mesh with said screw for moving said stitching member laterally of said core as said stitching member contacts the work.
5. In a tire-building apparatus the combination of an annular tire core, means for rotating the same, revolvable stitching members, supporting members for said stitching members provided with segmental threads, and means comprising a rotary member formed with right and left hand threads adapted automatically to be thrown into and out of mesh with said segmental threads as said stitching members engage and disengage the work for moving said stitching members laterally of said core and permitting them to be returned to their central positions.
6. In tire-building apparatus the combination of a tool head, tool-carrying members provided with segmental threads and slidably mounted on said tool head, revolvable stitching tools mounted upon said tool-carrying members, a revolvable right and left threaded member adapted to mesh with the segmental threads of said tool-carrying member and means for yieldingly holding said threaded member out of mesh with the segmental threads of said tool-carrying members.
7. In a tool-head for tire-building apparatus the combination of tool-carrying members provided with segmental threads, means for yieldingly pulling the same to-
ward each other, and a right and left threaded member adapted to be thrown into and out of mesh with the segmental threads of said tool-carrying members.
8. In a tool-head for tire-building apparatus the combination of tool-carrying members provided with segmental threads, means for yieldingly pulling the same toward each other, a right and left threaded member adapted to be brought into and out of mesh with the segmental threads of said tool-carrying members, and means adapted yieldingly to hold said right and left threaded member out of mesh with said segmental threads but to be overcome by the pressure of the tools against the work.
9. In tire-building apparatus the combination of an annular tire core adapted to be rotated circumferentially, a stitching tool, a tool-carrying member adapted to carry said tool in a direction substantially radial of said core, means for positively feeding said tool away from the middle plane of the core, a power member for feeding it inward, a yielding connection between said power member and tool, and a roller mounted upon said tool-carrying member and so positioned as to stop the radially inward movement of said tool-carrying member at a predetermined position.
10. In a tire-building apparatus the combination of a frame, a tire core rotatably mounted thereon, a tool-carrying lever pivoted to said frame, a wheel journaled at the pivotal point of said lever, a tool-head mounted upon said lever, a screw journaled in said tool-head, a wheel secured to said screw, a driving member connecting said wheels, and means for moving said lever about its pivotal axis.
11. In tire-building apparatus the combination of a tire core adapted to be rotated circumferentially, a tool adapted to work upon a tire mounted on said core, a tool-head adapted for positively feeding said tool laterally of the tire as said tool-head is moved toward the axis of the tire, and means for so moving said tool-head comprising a toggle and a spring connected thereto and adapted to act upon said toggle with a diminishing force.
12. In tire-building apparatus the combination of a rotatable tire core, a tool head, means for yieldingly urging said tool head toward said core, in the plane thereof, a pair of stitching rollers mounted on said tool head, and positive driving means adapted to be thrown into action by contact of said stitching rollers with the work, for gradually feeding said stitchers laterally of the work.

In witness whereof I have hereunto set my hand this 28 day of January, 1921.

CURT KUENTZEL.
